UNITED STATES PATENT OFFICE.

PERRY BROWN, OF CORAOPOLIS, PENNSYLVANIA; MARGARET J. BROWN EXECUTRIX
OF SAID PERRY BROWN, DECEASED.

HAND-BRAKE FOR RAILWAY-CARS.

1,340,323.

Specification of Letters Patent. Patented May 18, 1920.

Application filed December 12, 1917. Serial No. 206,806.

To all whom it may concern:

Be it known that I, PERRY BROWN, a citizen of the United States, and a resident of Coraopolis, in the county of Allegheny and 5 State of Pennsylvania, have invented certain new and useful Improvements in Hand-Brakes for Railway-Cars, of which the following is a specification.

This invention relates to improvements in 10 hand brakes for railway cars, particularly of the type shown in my Patent No. 1,185,974, granted June 6, 1916, in which there is an operating handle arranged to drop by gravity to an inactive position. 15 The object of this invention is to improve the details of the brake shown in my aforesaid patent.

The invention consists in the combination and arrangement of parts the preferable 20 embodiment of which is hereinafter described and shown in the drawings accompanying and forming part hereof.

In the aforesaid drawings:

Figure 1 is a side elevation of a brake constructed in accordance with my invention.

Fig. 2 is a vertical central section of the same.

Fig. 3 is a vertical section taken at right angles to that shown in Fig. 2.

Fig. 4 is a view of an end of a passenger car having my brake applied thereto.

Fig. 5 is a perspective view of the chain pulley or drum.

Fig. 6 is a horizontal section of the chain 35 pulley or drum.

Fig. 7 is a plan view of the same.

Fig. 8 is a perspective view of the main part of the casing and part of the brake chain, the interior parts being removed.

Fig. 9 is a perspective view of the operating handle.

Fig. 10 is a section of that part of the handle which is within the casing.

Fig. 11 is a perspective view of the holding dog.

Fig. 12 is a view of an end of a freight car having my invention applied thereto.

Fig. 13 is a perspective detail.

Fig. 14 is a perspective view of the divisional wall or partition.

Fig. 15 is a sectional view showing my invention in a form in which it can be operated from opposite sides of a car wall, the

brake in this instance being supplied with two handles on opposite sides of the car wall. 55

Fig. 16 is a perspective view of the interior parts of the form shown in Fig. 15, said parts being shown separated in order that their structure may better appear.

Fig. 17 is a perspective view of an arrangement for operating the holding dog from opposite sides of the car wall.

Fig. 18 is a view of a modified form very similar to that shown in Fig. 15.

Fig. 19 is a perspective detail of one of 65 the parts shown in Fig. 17.

Referring now to the details of the drawings by numerals: 1 designates a casing, illustrated in Figs. 1 and 6 as being provided with an integral bracket 3 by which 70 the casing may be secured in position, and with two tubular downwardly extending members 4 and 5 through which the brake chain may pass. The integral bracket 3 is designed particularly to be secured to the 75 under side of the hand rail of a passenger car, as indicated in Fig. 4, but it may also be secured to the end of a freight car by using an angle iron 7 as illustrated in Fig. 10. The casing 1 is preferably formed of 80 an integral casting, as illustrated in Fig. 6, and therefore preferably has its rear end closed by the back wall 9 (see Fig. 2) and its exposed front end closed by a cover or cap plate 10, a bolt 12 being employed which 85 passes through the cover or cap plate 10 and the back wall 9, the bolt serving not only the purpose of securing the parts together but of supporting all the parts within the casing as will now be described. Journaled upon the 90 aforesaid bolt 12 and located against the back wall 9 is a chain pulley or drum 14 which is preferably of the construction which will be hereinafter described. The casing is provided with an annular projection 16 (see Fig. 8) which is provided with two projections 17 and 18 shown in Figs. 1 and 8. Against the annular projection 16 is fitted a divisional wall or partition 20 provided with a central aperture 22, see Fig. 14, 95 and with two recesses 24 and 25 which are arranged in registry with the aforesaid projections 16 and 18 so that when the divisional wall or partition 20 is placed in position the projections 17 and 18 enter the recesses 24 and 25 and prevent any movement 100 105

of the divisional wall or partition 20. Said divisional wall or partition is also provided with a cam projection 26 to be hereinafter referred to. The opening 22 in the center of 5 the divisional wall or partition 20 is just of the proper size to receive and provide a bearing for a journal 30 projecting from the chain pulley or drum hereinbefore referred to. The projecting end of the journal 30 is 10 formed of irregular shape, shown in Fig. 5 with four flat sides, which is designed to receive and support a ratchet wheel 32 (see Figs. 1 and 2). The aforesaid divisional wall or partition 20 is also provided with a 15 trunnion 34 forming a support for a pivoted dog 36 provided with a weighted handle 38 shown in Figs. 1 and 11, the dog being arranged in normal position to co-act with the aforesaid ratchet wheel 32 and prevent counter-rotation thereof.

The aforesaid chain pulley or drum 14 is made of the construction shown best in Figs. 5, 6 and 7, from which it will be seen that it is in the nature of a sprocket wheel. It is 20 particularly and especially designed to receive the standard brake chain now adopted by the various railroads so that the mechanics in applying my brake can cut off the proper length of the standard chain and 25 therefore not be obliged to keep in supply a special chain. Furthermore, if a chain should break in service, it can be easily replaced by the standard chain found on hand in all railroad repair shops. To this end the 30 chain pulley or drum 14 is provided with flat seats to receive and support the sides of the horizontally disposed links and with recesses having curved seats to receive the 35 outside curved surfaces of the vertically disposed links. The said flat seats are numbered 40 and in turn have corner lugs specially formed so that the two oppositely disposed lugs 41 at each corner fit partially around the curved end of the horizontally 40 disposed links so as to push against the end of the link when the pulley or drum is used to wind the spring to apply the brake, and the said curved recesses are designated 42 and are located between the aforesaid oppositely disposed corner lugs 41. Between the 45 flat seats 40 at the center thereof are center lugs 43 which are in just the proper location to enter between the sides of the horizontally disposed links and fit against the outside of the vertically disposed links. Furthermore, 50 the pulley or drum is provided with annular flanges 45 and 46 backing up the seats 40, so that the sides of the horizontally disposed links fit against the interior surfaces of said 55 flanges and are thereby effectively prevented from riding up from off their seats as power is applied to the pulley or drum to wind the chain and set the brake. I deem this construction of considerable importance for 60 65 while it is very common to provide chains

with pulleys having teeth, it is necessary in this brake to provide one which will be able to transmit the power exerted by the operating handle or lever to the chain pulley or drum in order to apply the brake in such a 70 manner that the pressure is so applied that the chain cannot work off of the pulley or drum.

In order to rotate the chain pulley or drum I employ a handle or lever similar to 75 that shown in my aforesaid patent, the lever in this case being shown in perspective view in Fig. 9. As there shown the operating handle, numbered 50, is provided with two apertures 51 and 52 through the first of 80 which passes the aforesaid bolt 12 which supports the various working elements of the brake. The opening 52 is designed to receive a trunnion 54 projecting from a pawl 55 shown in perspective view in Fig. 85 13. The operating handle or lever hangs from the bolt 12 and is provided with a large disk shaped member 56 which is almost as large as the opening in the casing and is provided with a flanged member 57 which closes 90 the recess in the casing shown at 60 in Fig. 8. The advantage of having the operating handle provided with the large disk shaped member such as 56 is that the lever is given a firm support and cannot move laterally 95 on the bolt 12, since the member 56 crowds up against the ratchet wheel 22 hereinbefore described. The pawl 55 co-acts with the teeth of the said ratchet wheel 32 as shown in dotted lines in Fig. 1 but when the handle 100 drops by gravity to an inactive position, the tail 62 of the pawl swings into the cam shaped recess on the lug 26 shown on the divisional wall or partition 20 illustrated in Fig. 14. It will be understood that as soon 105 as the operator moves the operating handle 50 to the left, as shown in Fig. 1, the pawl 55 and its tail 62 are also moved to the left with said handle, and in so doing the pawl is swung into engagement with the ratchet 110 wheel owing to the fact that the preponderance of weight is on the right hand side of the trunnion 54 as viewed in said Fig. 1. The said pawl 55 is provided with a handle 115 120 125 130 135 140 145 150 155 160 165 170 175 180 185 190 195 200 205 210 215 220 225 230 235 240 245 250 255 260 265 270 275 280 285 290 295 300 305 the ratchet wheel and the operator may, by holding the lever 50 against the tension of the brake chain, use his other hand to release the holding dog 36, when he will permit the handle to be moved downwardly against the pressure of his hands, for the distance of one tooth, or as many teeth as desirable, and when the brake has been released to the proper extent he will permit 16 the holding dog to reengage the ratchet wheel. I deem this of importance.

The tubular extensions 4 and 5 may have pipes 6 and 8 connected to them as shown in Figs. 1, 3 and 4 which form housings for the chain, and the free end of the chain may be provided with a flanged retainer 11 which will prevent the free end of the chain from being pulled out of the pipe 8 and into the casing 1 when the brake is released. Or, 20 when the pipe 8 is not employed the free end of the chain may be connected, by a bolt 13 or otherwise, to an eye 15 cast on the bottom of the casing (see Figs. 1 and 8). When both pipes 6 and 8 are employed, I use a 25 doubly flanged step or floor plate 19, as shown in Fig. 7.

In the form in which my invention is shown in Figs. 15, 16 and 17, I show my invention applied to a car wall so that the 30 brake may be operated both from the inside and outside of the car. To this end, I provide a chain pulley or drum 80 very similar to that shown in Fig. 5, except that it is provided with an extension 81 which passes 35 into the wall of the car. A telescopic extension 82 is employed which fits over the angular shaped projection 81 and turns therewith, this extension in turn having an angular shaped projection 83 which fits into 40 a ratchet wheel 84 located within an additional casing 85 and which is operated by a handle or lever 86 similar to that shown in Fig. 9. Owing to the telescopic feature it will be readily observed that my brake may 45 be applied to car walls of different thicknesses. With this form a bolt 88 is provided which connects both casings and all the operating parts together, and supports the operating members in both casings. 50 When this form of brake is used I employ a rock shaft 90 (see Fig. 17) which passes through the car wall and has an operating handle 91 on the inside of the car and a crank 92 on the outside of the car wall so 55 arranged that if any one on the inside of the car wishes to release the brake all that he has to do is to lift the handle 91 and the crank 92 will be turned until it strikes against the holding dog 93 when it will lift 60 the same and release the brake. It will be observed that the shaft 90 passes telescopically into a sleeve 94 formed on the crank 92 so that the shaft 90 may be adjusted with respect to the crank 92 to enable the arrangement 65 to be used on different thicknesses of

car walls. In the event that it is not necessary to have the telescopically adjustable drum for use on different thicknesses of wall, the whole drum with extensions on opposite sides thereof may be made of one 70 integral casting as shown in Fig. 18. In this case the drum is numbered 95 and one extension is numbered 96 to receive and support a ratchet wheel 97 and the other extension is numbered 98 to receive and support 75 the ratchet wheel 99.

It will be obvious that modifications and variations may be made without departing from the spirit of my invention, the scope of which is set forth by the appended claims. 80

What I claim as my invention is:

1. In a hand brake for cars and the like, the combination of a casing, a brake tightening element, a ratchet wheel, a hand lever, a pawl operated from said lever co-acting 85 with said ratchet wheel, and a handle on said pawl projecting through the casing, whereby an operator may move the pawl handle to move or hold the pawl out of engagement with said ratchet wheel. 90

2. In a hand brake for cars and the like, the combination of a casing, a brake tightening element, a ratchet wheel, a hand lever, arranged to rotate said ratchet wheel upon the 95 movement of said handle, a dog arranged to hold the ratchet wheel from counter-rotation, and a handle on said pawl projecting through the casing whereby an operator may move the pawl handle to move or hold 100 the pawl out of engagement with said ratchet wheel and permit the ratchet wheel to move a tooth at a time and hold the same as desired by the aforesaid holding dog. 105

3. In a hand brake for cars and the like, the combination of a casing, a drum therein, a brake tightening element operated by said drum, a ratchet wheel moving with said drum, a hand lever having a pawl co-acting with said ratchet wheel and arranged to drop by gravity to an inactive position, and a handle on said pawl projecting through the casing, whereby an operator may move the pawl handle to move or hold 110 the pawl out of engagement with said ratchet wheel. 115

4. In a hand brake for cars and the like, the combination of a casing, a brake tightening element, a ratchet wheel, a hand lever 120 having a pawl co-acting with said ratchet wheel and arranged to drop by gravity to an inactive position, and a handle on said pawl projecting through the casing, whereby an operator may move the pawl handle 125 to move or hold the pawl out of engagement with said ratchet wheel.

5. In a hand brake for cars and the like, the combination of a casing, a brake tightening element, a ratchet wheel, a hand lever 130

- having a pawl co-acting with said ratchet wheel and arranged to drop by gravity to an inactive position, a dog arranged to hold said ratchet wheel from counter-rotation, 5 and a handle on said pawl projecting through the casing, whereby an operator may move the pawl handle to move or hold the pawl out of engagement with said ratchet wheel.
- 10 6. In a hand brake for cars and the like, the combination of a brake tightening element, a ratchet wheel, a hand lever, a pawl operated from said lever and arranged to rotate said ratchet wheel upon the movement 15 of said handle, a holding dog, said lever being arranged to drop by gravity to a substantially vertical position and thereby cause the pawl to disengage said ratchet wheel, and a handle on said pawl whereby 20 an operator may move the pawl handle to move or hold the pawl out of engagement with said ratchet wheel and permit the ratchet wheel to move a tooth at a time and hold the same as desired by the aforesaid 25 holding dog.
7. In a hand brake for cars and the like, the combination of a casing, a drum therein, a brake tightening element operated by said drum, a ratchet wheel moving with said 30 drum, a hand lever having a pawl co-acting with said ratchet wheel, said hand lever being arranged to drop by gravity to an inactive position and move the pawl out of contact with said ratchet wheel, and a handle 35 on said pawl projecting through the casing, whereby an operator may move the pawl handle to move or hold the pawl out of engagement with said ratchet wheel.
8. In a brake, the combination of a chain 40 tightening element, a ratchet wheel, a hand lever normally hanging by gravity, and a pawl pivotally carried by said hand lever and movable into and out of contact with said ratchet wheel, said pawl having a handle 45 permitting it to be manually moved independently of said lever.
9. In a brake, the combination of a chain 50 tightening element, a ratchet wheel, a hand lever normally hanging by gravity, a pawl carried by said hand lever, and a cam for moving said pawl out of engagement with said ratchet wheel as said hand lever drops to its normal position.
10. In a brake, the combination of a chain 55 tightening element, a ratchet wheel, a hand lever normally hanging by gravity, a pawl carried by said hand lever, and a cam for moving said pawl out of engagement with said ratchet wheel as said hand lever drops 60 to its normal position, said pawl having a handle permitting it to be manually moved independently of said lever.
11. In a brake, the combination of a casing, 65 a chain tightening element, a ratchet wheel, and a disk-like member journaled in
- in said casing alongside of said ratchet wheel, said disk-like member having a hand lever projecting outside of the casing and arranged to drop by gravity to a normally inactive position. 70
12. In a brake, the combination of a casing, a chain tightening element, a ratchet wheel, a disk-like member journaled in said casing alongside of said ratchet wheel, a hand lever projecting from said disk-like member through said casing, a pawl movably carried by said hand lever to co-act with said ratchet wheel, and a cam in the casing for moving said pawl out of engagement with said ratchet wheel as said hand lever drops by gravity. 75
13. In a brake, the combination of a casing, a chain tightening element, a ratchet wheel, a disk-like member journaled in said casing alongside of said ratchet wheel, a hand lever projecting from said disk-like member through said casing, a pawl movably carried by said hand lever to co-act with said ratchet wheel, and a cam in the casing for moving said pawl out of engagement with said ratchet wheel as said hand lever drops by gravity, said pawl having a handle permitting it to be manually moved independently of said lever. 80
14. In a brake, the combination of a casing having a rear end and open at its front, a drum therein, a divisional wall or partition in said casing having a part of the drum finding a bearing therein and projecting therethrough, a ratchet wheel carried by said projecting part on the outside of said partition, a hand lever supported adjacent said ratchet wheel, said hand lever having a pawl arranged to co-act with and rotate the ratchet wheel as said hand lever is moved upwardly, and a cam shaped member in said casing arranged to move said pawl out of contact with said ratchet wheel as said hand lever moves downwardly. 95
15. In a brake, the combination of a casing having a rear end and open at its front, a drum therein, a divisional wall or partition in said casing having a part of the drum finding a bearing therein and projecting therethrough, a ratchet wheel carried by said projecting part on the outside of said partition, a hand lever supported adjacent said ratchet wheel, said hand lever having a pawl arranged to co-act with and rotate the ratchet wheel as said hand lever is moved upwardly, a cap plate, and a bolt passing through said parts and securing the cap plate to the casing and supporting the drum, the ratchet wheel and hand lever. 100
16. In a brake, the combination of a casing having a rear end and open at its front, a drum therein, a divisional wall or partition in said casing having a part of the drum finding a bearing therein and projecting therethrough, a ratchet wheel carried by 115
- 120
- 125
- 130

- said projecting part on the outside of said partition, a hand lever supported adjacent said ratchet wheel, said hand lever having a pawl arranged to co-act with and rotate the 5 ratchet wheel as said hand lever is moved upwardly, a cam shaped member in said casing arranged to move said pawl out of contact with said ratchet wheel as said hand lever moves downwardly, a cap plate, 10 and a bolt passing through said parts and securing the cap plate to the casing and supporting the drum, the ratchet wheel and hand lever.
17. In a brake, the combination of a casing having a rear end and open at its front, 15 a drum therein, a divisional wall or partition in said casing having a part of the drum finding a bearing therein and projecting therethrough, a ratchet wheel carried by said 20 projecting part on the outside of said partition, a hand lever supported adjacent said ratchet wheel, said hand lever having a pawl arranged to co-act with and rotate the ratchet wheel as said hand lever is moved upwardly, 25 and a cam shaped lug on said partition arranged to be contacted with by said pawl to move the same out of contact with said ratchet wheel as said hand lever is moved downwardly.
- 30 18. In a brake, the combination of a casing having a rear end and open at its front, a drum therein, a divisional wall or partition in said casing having a part of the drum finding a bearing therein and projecting therethrough, a ratchet wheel carried by said 35 projecting part on the outside of said partition, a hand lever supported adjacent said ratchet wheel, said hand lever having a pawl arranged to co-act with and 40 rotate the ratchet wheel as said hand lever is moved upwardly, a cam shaped lug on said partition arranged to be contacted with by said pawl to move the same out of contact with said ratchet wheel as said hand 45 lever is moved downwardly, and a handle on said pawl projecting through the casing whereby an operator may move said handle to take the pawl out of engagement with said ratchet wheel.
- 50 19. In a car brake, the combination of a chain tightening element, a hand lever arranged to drop by gravity to an inoperative position and to rotate the said chain tightening element on an upward movement of 55 said hand lever, said chain tightening element having a series of flat portions to receive and support the horizontal links of a chain, projections at the ends of said flat portions to act upon the curved ends of the 60 links, recesses between said flat portions to receive the vertical links, and lugs projecting up from said recesses between the flat portions to enter between the sides of the links resting upon the flat portions.
- 65 20. In a car brake, the combination of a 70 chain tightening element, a hand lever arranged to drop by gravity to an inoperative position and to rotate the said chain tightening element on an upward movement of said hand lever, said chain having a series of 75 flat portions to receive and support the horizontal links of a chain, projections at the ends of said flat portions to act upon the curved ends of the links, recesses between said flat portions to receive the vertical links, and lugs projecting up from said recesses between the flat portions to enter between the sides of the links resting upon the flat portions, and flanges upon opposite sides of said flat portions against which the sides 80 of the horizontal links contact.
21. In a car brake, the combination of a chain tightening element, a ratchet wheel movable therewith, a hand lever arranged to drop by gravity and to rotate said ratchet 85 wheel and chain tightening element on an upward movement of said hand lever, said chain tightening element having a series of flat portions to receive and support the horizontal links of a chain, projections at the 90 ends of said flat portions to act upon the curved ends of the links, recesses between said flat portions to receive the vertical links, and lugs projecting up from said recesses between the flat portions to enter between the sides of the links resting upon the flat portions.
22. In a car brake, the combination of a chain tightening element, a ratchet wheel movable therewith, a hand lever arranged to drop by gravity and to rotate said ratchet 95 wheel and chain tightening element on an upward movement of said hand lever, said chain tightening element having a series of flat portions to receive and support the horizontal links of a chain, projections at the ends of said flat portions to act upon the curved ends of the links, recesses between said flat portions to receive the vertical links, and lugs projecting up from said recesses between the flat portions to enter between the sides of the links resting upon the flat portions.
23. In a car brake, a chain tightening element having a series of flat portions to receive and support the horizontal sides of the chain links, recesses between said flat portions to receive the vertical links, and projections between said flat portions forming the ends of said recesses and arranged to enter the said horizontal links between the ends of said vertical links, in combination 100 with a ratchet wheel movable with said chain tightening element, and a swinging lever having a pawl engageable with said ratchet wheel to rotate said chain tightening element.
24. In a car brake, a chain tightening ele- 105 110 115 120 125 130

- ment having a series of flat portions to receive and support the horizontal sides of the chain links, flanges on the exterior sides of said flat portions to confine the sides of said links, recesses between said flat portions to receive the vertical links, and projections between said flat portions forming the ends of said recesses and arranged to enter the said horizontal links between the ends of 5 said vertical links, in combination with a ratchet wheel movable with said chain tightening element, and a swinging lever having a pawl engageable with said ratchet wheel to rotate said chain tightening element.
- 15 25. In a car brake, a chain tightening element having a series of flat portions to receive and support the horizontal sides of the chain links, lugs at the ends of said flat portions to engage the rounded ends of said 10 horizontal links, recesses between said flat portions to receive the vertical links, and projections between said flat portions forming the ends of said recesses and arranged to enter the said horizontal links between the ends of 15 said vertical links, in combination with a ratchet wheel movable with said chain tightening element, and a swinging lever having a pawl engageable with said ratchet wheel to rotate said chain tightening element.
- 20 30. In a car brake, a chain tightening element having a series of flat portions to receive and support the horizontal sides of the chain links, lugs at the ends of said flat portions to engage the rounded ends of said 25 horizontal links, recesses between said flat portions to receive the vertical links, and projections between said flat portions forming the ends of said recesses and arranged to enter the said horizontal links between the ends of 30 said vertical links, in combination with a ratchet wheel movable with said chain tightening element, and a swinging lever having a pawl engageable with said ratchet wheel to rotate said chain tightening element.
- 25 35. In a car brake, a chain tightening element having a series of flat portions to receive and support the horizontal sides of the chain links, flanges on the exterior sides of said flat portions to confine the sides of said links, lugs at the ends of said flat portions to engage the rounded ends of said horizontal links, recesses between said flat portions to receive the vertical links, and projections between said flat portions forming the ends of said recesses and arranged to enter the said horizontal links between the ends of 40 said vertical links, in combination with a ratchet wheel movable with said chain tightening element, and a swinging lever having a pawl engageable with said ratchet wheel to rotate said chain tightening element.
- 40 45. In a car brake, a chain tightening element having a series of flat portions to receive and support the horizontal sides of the chain links, flanges on the exterior sides of said flat portions to confine the sides of said links, lugs at the ends of said flat portions to engage the rounded ends of said horizontal links, recesses between said flat portions to receive the vertical links, and projections between said flat portions forming the ends of said recesses and arranged to enter the said horizontal links between the ends of 45 said vertical links, in combination with a ratchet wheel movable with said chain tightening element, and a swinging lever having a pawl engageable with said ratchet wheel to rotate said chain tightening element.
- 45 50. In a car brake, the combination of a casing, a drum therein, a brake chain over said drum, a hand lever arranged to drop by gravity to a normal position and to operate said drum on an upward movement of
- said hand lever to wind said chain, said chain having a free end projecting from the 55 casing, and means for preventing said end from being drawn entirely within the casing.
28. In a car brake, the combination of a casing, a drum therein, a brake chain over 60 said drum, a hand lever arranged to drop by gravity to a normal position and to operate said drum on an upward movement of said hand lever to wind said chain, said chain having a free end projecting from the 65 casing, an eye on said casing, and means for securing the free end of the chain to said eye to prevent said free end from being drawn through said casing.
29. In a car brake and in combination 70 with the wall thereof, a chain drum on one side of a car wall having flat sides to receive and support the flat sides of a link, and projections located between said flat sides to enter the links, a ratchet wheel movable with 75 said chain drum, a hand lever for operating said ratchet wheel and chain drum, a telescopically adjustable member projecting from said chain drum through said car wall, a ratchet wheel carried by said member, and 80 a hand lever on the opposite side of said wall to rotate said ratchet wheel and the afore- 85 said chain drum.
30. In a car brake, the combination of a chain tightening element on one side of a 90 car wall having a ratchet wheel movable therewith, a hand lever for operating said ratchet wheel and chain tightening element, a telescopically adjustable member projecting from said chain tightening element through 95 a car wall, a ratchet wheel carried by said member, a hand lever on the opposite side of said wall to rotate said ratchet wheel and the aforesaid chain tightening element, a dog co-acting with one of said ratchet wheels for holding said chain tightening element from counter-rotation, and a telescopically adjustable rock shaft passing through said wall for moving said pawl from the opposite side of the car wall. 100

In testimony whereof I affix my signature in presence of two witnesses.

PERRY BROWN.
